No. 760,615.

PATENTED MAY 24, 1904.

F. M. CROLIUS.

HERNIAL TRUSS.

APPLICATION FILED AUG. 26, 1902.

NO MODEL.

UNITED STATES PATENT OFFICE.

FRANK M. CROLIUS, OF MINNEAPOLIS, MINNESOTA.

HERNIAL TRUSS.

SPECIFICATION forming part of Letters Patent No. 760,615, dated May 24, 1904.

Application filed August 25, 1902. Serial No. 121,006. (No model.)

To all whom it may concern:

Be it known that I, FRANK M. CROLIUS, a citizen of the United States, residing in Minneapolis, county of Hennepin, and State of Minnesota, have invented certain new and useful Improvements in Trusses; and I hereby declare that the following is a full, clear, and exact description thereof, such as will enable those skilled in the art to which my invention relates to properly construct and to use the same, reference being had to the accompanying drawings.

My invention relates generally to trusses for hernia, and particularly to that class thereof in which are employed belts, straps, and one or more "pads" for engaging the affected parts of the wearer; and it consists in the peculiar construction of certain parts, herein illustrated, described, and claimed.

The objects of my invention are, first, to provide a novel and improved truss-plate adapted to universal adjustment of the pad or pads, and, second, to provide a truss-plate equipped with flexible buttons or fasteners by means of which the belts and straps may be more quickly attached and detached than are those at present in use.

To these ends my invention consists of the appliance shown in the accompanying drawings, in which—

Figure 1 is a perspective complete; Fig. 2, a front elevation of a portion of the truss-plate detached; Fig. 3, the same, showing a modified form of opening for the attachment of the pad; Fig. 4, the same, showing another form of opening; and Fig. 5, the same, showing still another form of opening.

Similar letters refer to similar parts throughout the several views, A being the truss-plate, B the belt, C the straps, D the pad, E the fastener, and F the clamp-bolt.

The truss-plate A may be made of any suitable material, aluminium being well adapted to the purpose. This plate may be fashioned in any desired form; but I prefer the configuration herein shown, this being best adapted to the purposes of trusses in general. It is laterally pierced to receive the clamp-bolt for securing the pads thereto. These perforations are an important feature of my inven-

tion and are so configurated as to provide for universal adjustment and secure attachment of the openings of the pads. I show herein four different forms of openings, either one of which is adapted to the purpose, but 55 have a preference as to which form I use—viz., the one shown in Figs. 1 and 2.

In Fig. 1 I show an improved fenestrated truss-plate having affixed thereto two pads adapted to application to double rupture, and 60 in all of the figures I show the adaptation of my fenestrations to the purpose of universal adjustment, thereby adapting them for use in all cases of inguinal, scrotal, femoral, and ventral hernia.

It is apparent that my plates A are also adapted to the use of specially-constructed pads adapted to the relief of varicocele. These plates A, I fashion of sheet metal, (preferably aluminium,) their general configuration being 70 as herein shown, that form being best adapted to the purpose.

The novel feature of my truss-plate is the peculiar configuration of the openings therein by means of which I affix my pads thereto. 75 These openings a , a' , a'' , and a''' are each and all adapted to universal adjustment of the pads D, as will be seen by the drawings. The first of these several forms of opening (and the form which I prefer) is shown by a in 80 Figs. 1 and 2. It consists of two horizontal openings connected by a vertical slit. This opening (in combination with a slit herein-after described in the pad D) permits of all possible variations in positions of the said 85 pads. In Fig. 3 I show another form of opening, a' . It consists of three slits crossing each other, or, in other words, an opening having six radial portions. In Fig. 4 I show still another form of opening, a'' , which opening 90 consists of a spiral, and in Fig. 5 I show still another form of opening, a''' , which consists of a reversed-arranged semicircular slit of the form of a letter S.

Any and all of these forms are adapted to the purposes specified, it being 95 my purpose to provide a single opening in each end of a truss-plate, which opening shall be adapted for adjustment of the pads therewithout removal of the clamp-screw therefrom.

The belt B and straps C are not unlike those commonly used, hence need no description herein. So, too, the pads D herein shown are common to trusses of this character and need no detailed description. As herein shown, they consist of ovate blocks adapted to overlie and press upon the affected parts and to prevent displacement. These pads D may be made of metal, rubber, celluloid, or other suitable material. Their flat sides (the sides next the plates A) are respectively provided with plates having transverse slits, as shown by dotted lines in Figs. 2, 3, 4, and 5, underneath which (within the pad) is a longitudinally-movable interiorly-threaded "nut," into which the exteriorly-threaded clamp-bolt F screws to secure the said pad D to the said plate A. This clamp-bolt and nut are common to trusses in general.

The fasteners E, commonly designated as "ball-and-socket" fasteners, constitute an independent invention and are in daily use for many purposes, are especially adapted to, but, so far as my knowledge extends, have never been used for, the purpose of connecting belts and straps to truss-plates, and I therefore claim their application to this purpose. Their construction is so generally known that I do not deem it necessary to specify it herein. The "ball" or male portion *f* of these fasteners I affix in my plate substantially as herein shown, three in each end of the plate, the four upper ones being adapted to attachment to the belt A and the two lower ones, *b' b'*, being adapted to the attachment of the straps C. The belt A is equipped at each end with adjustable clasps or buckles *d*, to each of which are affixed two short straps *e*, to which straps in turn are affixed the "sockets" or female portions of the fasteners E.

The straps C (two in number) are adjustable as to length by means of suitable clasps or buckles *f*, are looped upon the belt A at their rear (upper) ends, while their front (lower) ends are equipped with the sockets or female portions of the fasteners E, by means of which they are secured to the truss-plates A by pressing the socket or female portions of the said fasteners E affixed thereto onto and over the male portions of the fasteners E affixed in the plate A.

The clamp-bolt F is not unlike those commonly used, consisting of an exteriorly-threaded shaft portion adapted to engagement with the interiorly-threaded nut longitudinally movable within the transverse slit of the pad D. For convenience its head portion is provided with a swiveled ring, by means of which it may be rotated in securing or releasing the said pads D. It will be seen that by having continuous openings in the plate A it is not necessary at any time to remove the clamp-bolt therefrom in adjusting the pads D to their multitudinous adjustments, but simply loosen the same in moving the pad to the desired position and then tightening the same.

What I claim as new, and desire to secure by Letters Patent, is—

As a new article of manufacture, a truss-plate formed with two parallel longitudinal slots connected by a transverse slot, a clamping-bolt adapted to slide in said slots, in combination with the pad formed with a transverse slit through which said bolt extends, and a nut on the threaded end of said bolt.

FRANK M. CROLIUS.
